UNITED STATES PATENT OFFICE.

JAMES JESSEN, OF MINNEAPOLIS, MINNESOTA.

IGNITION MECHANISM FOR COMBUSTION-ENGINES.

1,377,688.

Specification of Letters Patent. Patented May 10, 1921.

Application filed August 16, 1919. Serial No. 318,004.

To all whom it may concern:

Be it known that I, JAMES JESSEN, a citizen of the United States, residing at Minneapolis, county of Hennepin, State of Minnesota, have invented certain new and useful Improvements in Ignition Mechanism for Combustion-Engines, of which the following is a specification.

My invention relates to ignition mechanism for low compression internal combustion engines and the object of the invention is to provide self-contained mechanism for the ignition of the combustible charges in high speed engines of the low compression type, and especially in engines of the two stroke cycle and means for controlling the time of ignition without the use of electric or other attachments.

The invention is particularly applicable to the engine shown and described in my Patents Numbers 1,325,294, granted Dec. 16, 1919, and 1,330,874, granted Feb. 17, 1920, and consists generally in various constructions and combinations, all as hereinafter described and particularly pointed out in the claims.

In the accompanying drawings forming part of this specification,

Figure 1 is a vertical section of an engine having my invention applied thereto and showing the engine midway on the compression stroke,

Fig. 2 is an enlarged section of the ignition mechanism, showing it ninety degrees of the crank revolution later and at the point of ignition.

Fig. 3 is a vertical section on the line 3—3 of Fig. 2, showing the operating parts in the position as in Fig. 1,

Fig. 4 is a horizontal section on the line 4—4 of Fig. 2,

Fig. 5 is a similar section on the line 5—5 of Fig. 2,

Fig. 6 is a vertical section similar to Fig. 3, but showing the parts 180 degrees of the crank throw later.

In the drawing, 28 represents the combustion cylinder, 43 the piston working therein, 45 the connecting rod and 21 the crank shaft, 50 mounted in suitable bearings in the crank case 20. 28 is the compression and combustion chamber, 55 the admission port for combustion to the cylinder and 53^b the exhaust ports. 72 is a fuel atomizer and gas producer from which gas is admitted through the passage 56 to the port 55. 40 is the pump

cylinder for combustion and 49 the valve piston working therein, 38 is the pump cylinder for air, 46 the piston therein, 47 the connecting rod to the pump crank shaft 22, 60 and 62 a piston rod connecting the pistons 46 and 49. The crank shafts 21 and 22 are geared together to run at the same speed and the pump shaft crank 48 is running substantially ninety degrees ahead of the combustion cylinder crank 44, so that when the combustion cylinder piston is at the end of its stroke, the pump pistons are at the center of their stroke, and vice versa. The head 50 of the pump cylinder 40 is preferably detachable and is formed with a cylindrical casing 27 and a compression chamber 29. The bore 30 of the cylinder casing 27 has a communication with the compression chamber 29 through a port 31 and also 75 through a port 32 and transfer duct 33 with the compression chamber 28 of the combustion cylinder. I prefer to form the transfer duct 33 in a gooseneck 140, secured to the head 27 and to the neck 37 of the combustion cylinder head 36, all being surrounded by cooling water. A plunger 38 is accurately fitted in the cylindrical bore 30 and is attached to the valve piston 49 by means of a rod 39, passing through the head 50 and 80 being preferably an extension of the rod 62. The plunger has an internal bore 36 fitting accurately a plug 41, having a centering shoulder 42 and flange 51 to be received in a counterboard seat in the casing 27. The 85 flange 51 is held to its seat by a plate 52, secured to the casing 27 by screws 54. A semi-cylindrical bore 56 connecting with the bore 30 and the port 32 is provided with an accurately fitted circular plug 57, having 90 one side 58 recessed to correspond to the form of the bore 30. The plug is provided with internal threads and a threaded rod 60, having a shoulder 61 fitted against the under side of the plate 52 and is screwed into 100 the internal thread 59. The rod extends through the plate 52 and is provided with a bevel gear 63 or other means for turning the rod to adjust its longitudinal position. The plunger 38 has a counter bore 64, a 105 port 65 and a semi-circular peripheral groove 66.

The cylinder casing 27 is provided with a small trap chamber 67, the area of which is adjustable by means of a screw 68, having a 110 check nut 69. A port 70 leads from the trap chamber to the bore of the cylinder and is

adapted to register with the port 65 and groove 66 of the plunger at certain points during its strokes. An exhaust port 68' is arranged in the upper end of the bore and an exhaust pipe 69' may be connected to the exhaust pipe of the engine. In operation, and starting with the position of the pistons as in Fig. 1, the power piston on its compression stroke is forcing a small portion of the combustible charge through the transfer duct 33 and port 32 into the bore 30 below the plunger and into the compression chamber 29. At the completion of the down stroke of the plunger as shown in Fig. 6, the combustible gas has been compressed in the chamber 29 and is now flowing down through the port 31 and plunger bore 36 drawing the spent gases in the plunger through the counterbore 64 and exhaust port 68 and filling the plunger bore with combustible gas. Upon the next upward stroke of the plunger, the gas is compressed in the plunger bore, and as the port 65 passes through trap port 70 a portion of the compressed charge is transferred to the trap 67. The remainder is compressed to the ignition point in the small ignition chamber 71 between the plug and the bottom wall 72 of the plunger. On the succeeding down stroke, as the port 65 passes below the plug 41, the burning gases will ignite the gases in the trap chamber 67 through the port 65. The space between the port 65 and groove 66 is slightly longer than the width of the port 70 and as the groove comes to a register with the port, the burning gases under high pressure will pass around the groove to the chamber 73. This chamber being filled with combustible gas under compression from the combustion cylinder, the gas is immediately ignited and the resulting pressure instantly transfers the combustible gas to the main cylinder. The point of ignition is controlled by the vertical position of the plug 57, and as the plug is lowered, the ignition occurs later and may be entirely shut off by lowering the plug to close the port 32. On the further down stroke of the plunger, the burning gases in the plunger bore are expanded until exhausted. During each upstroke of the plunger when the groove 66 passes the ignition port leading to the main cylinder which is then in the exhaust period, the burning gases remaining in the groove and trap is exhausted through the port 32 and duct 33 to the main cylinder. It will be seen that with this simple construction, no valves or other accessories are necessary to transfer or control the time of ignition. The cooling of the ignition charge between the first ignition point and its transfer to the combustion cylinder is prevented by means of successive ignition of the trapped combustible gases. The diameter of the ignition plug and the area of the ports are

made as small as possible, but large enough to prevent too rapid cooling.

It is evident that various modifications may be made in the construction without departing from the principle and scope of the invention. For example, pure air may be compressed to a high enough pressure and temperature for ignition, or a small part of combustion may be introduced into the ignition chamber from the pump cylinder 40. Other means of varying the time of ignition may be provided and I do not, therefore, limit myself to the exact construction shown.

I claim as my invention:

1. An ignition device for internal combustion engines comprising in combination with a low compression power cylinder and piston working therein, an auxiliary cylinder having an ignition chamber, a conduit between said cylinders, a compression plunger working in the auxiliary cylinder, said plunger arriving at maximum compression in advance of the power piston, means controlled by the compression plunger for admitting combustible gas to the ignition chamber from the power cylinder, means co-acting with said plunger for compressing said gas to the ignition point and means controlled by the plunger, for thereafter conducting the ignited gas from the ignition chamber to the power cylinder. 80

2. In an ignition device for internal combustion engines, the combination with a low compression power cylinder and piston working therein, of an auxiliary cylinder having an ignition chamber, a compression plunger working in the auxiliary cylinder, said plunger arriving at maximum compression in advance of the power piston, a charging chamber in said auxiliary cylinder, means controlled by the plunger for admitting combustible gas to said charging chamber from the power cylinder and transferring said gas to the ignition chamber, means co-operating with said plunger for compressing said gas to ignition pressure and for thereafter conducting the ignited product from the ignition chamber to the power cylinder for the ignition of a power charge. 100

3. An ignition device comprising a cylinder, a hollow compressor in said cylinder, a low compression chamber in said cylinder, a high compression ignition chamber in said compressor, a port in said cylinder for admitting gaseous fluid to said low compression chamber, a port in said compressor for transferring said fluid to the high compression chamber, a second chamber having a cylindrical port, said port being swept by the compressor port and a peripheral channel in said compressor sweeping said cylinder port. 115

4. In an ignition device for internal combustion engines, the combination with a low compression power cylinder and piston 130

- working therein and means for charging said power cylinder with a combustible mixture of an auxiliary ignition cylinder having an ignition chamber, a compression plunger working in said ignition cylinder, said plunger coming to maximum compression in advance of the power piston, a conduit between said cylinders open to the power cylinder, a charging chamber in said auxiliary cylinder, means controlled by the compression plunger for admitting combustible gas through the conduit to said charging chamber and transferring said gas to the ignition chamber, mechanism coacting with said compression plunger for compressing said gas to ignition pressure and thereafter contacting the ignited gas with combustible mixture in said conduit to ignite the power charge and means for exhausting the ignition gases.
5. The combination with a low compression internal combustion power cylinder and piston and means for charging said cylinder with a combustible mixture of an auxiliary ignition cylinder having an ignition chamber, a compression plunger working in said ignition cylinder, said plunger coming to maximum compression in advance of the power piston, a conduit between said cylinders open to the power cylinder, means controlled by the compression plunger for admitting combustible gas to the ignition chamber from the power cylinder, means coacting with the plunger for compressing said gas to ignition pressure, means controlled by the compression plunger for thereafter contacting the ignited gas with combustible mixture in the conduit to the power cylinder and means for varying the time of contact.
10. In an ignition device for internal combustion engines, the combination with a low compression power cylinder having a piston working therein and means for supplying a combustible power charge to said cylinder, of an auxiliary compression cylinder, having an ignition chamber and a charging chamber, a plunger working in said cylinder, means controlled by said plunger for passing combustible gas from said power cylinder to said charging chamber and from said charging chamber to said ignition chamber, means coöperating with said plunger for compressing said combustible to the ignition point and means controlled by the plunger for thereafter contacting the ignited product with the combustible gas in the power cylinder to ignite the power charge.
15. An ignition device comprising a cylinder, a hollow compression plunger working in said cylinder, a low compression charging chamber in said cylinder, a stationary piston co-acting with the hollow piston to form an ignition chamber, a conduit port controlled by said plunger for admitting gas to the charging chamber, a port in the plunger for transferring said gas to the ignition chamber, a trap port in said cylinder swept by said plunger port, a peripheral channel in said plunger periodically opening to said trap port and said conduit port.
20. An ignition device comprising a cylinder, a hollow compression plunger working in said cylinder, a charging chamber in said cylinder, an ignition chamber in said plunger, means controlled by said plunger for admitting gas to the charging chamber, a port in said plunger for transferring said gas to the ignition chamber, a trap port in said cylinder, said port being swept by said plunger port, an exit port from said cylinder, a peripheral channel in said plunger, periodically opening to said trap port and said exit port and means for varying the time of opening to said exit port.
25. An ignition device comprising a cylinder, a hollow compression plunger working in said cylinder, a charging chamber in said cylinder, an ignition chamber in said plunger, means controlled by said plunger for admitting gas to the charging chamber, a port in said plunger for transferring said gas to the ignition chamber, a trap port in said cylinder, said port being swept by said plunger port, an exit port from said cylinder, a peripheral channel in said plunger, periodically opening to said trap port and said exit port and means for varying the time of opening to said exit port.
30. An ignition device comprising a cylinder, a hollow compression plunger working in said cylinder, a charging chamber in said cylinder, an ignition chamber in said plunger, means controlled by said plunger for admitting gas to the charging chamber, a port in said plunger for transferring said gas to the ignition chamber, a trap port in said cylinder, said port being swept by said plunger port, an exit port from said cylinder, a peripheral channel in said plunger, periodically opening to said trap port and said exit port and means for varying the time of opening to said exit port.
35. An ignition device comprising a cylinder, a hollow compression plunger working in said cylinder, a charging chamber in said cylinder, an ignition chamber in said plunger, means controlled by said plunger for admitting gas to the charging chamber, a port in said plunger for transferring said gas to the ignition chamber, a trap port in said cylinder, said port being swept by said plunger port, an exit port from said cylinder, a peripheral channel in said plunger, periodically opening to said trap port and said exit port and means for varying the time of opening to said exit port.
40. In witness whereof, I have hereunto set my hand this 12th day of August 1919.
- JAMES JESSEN.
